UNITED STATES PATENT OFFICE.

ARTHUR M. BARRETT, OF WINNETKA, ILLINOIS.

TRUCK.

1,416,674.

Specification of Letters Patent. Patented May 23, 1922.

Application filed September 11, 1917. Serial No. 190,762.

To all whom it may concern:

Be it known that I, ARTHUR M. BARRETT, a citizen of the United States, and a resident of Winnetka, in the county of Cook, State 5 of Illinois, have invented certain new and useful Improvements in Trucks, of which the following is a specification, reference being had to the accompanying drawings.

My invention relates to trucks of the type 10 comprising an elevating frame which is adapted to be raised and lowered with reference to the fixed framework so as to be capable of being used with a plurality of loading platforms. It is one of the objects of 15 my invention to provide a form and arrangement of operating parts whereby the operation of raising the elevating frame can be performed in close quarters whether or not the steering and elevating lever can be operated precisely in the central longitudinally-extending vertical plane of the truck. It is one of the objects of my invention to 20 provide that the elevating frame may be raised by a succession of short strokes of the tongue or other operating lever when located either in the normal longitudinal position relative to the truck or at any other angle through a wide range as said lever is moved sidewise for guiding the truck. To 25 this end, it is one of the objects of my invention to provide a construction in which the operative portion of the operating lever is positioned substantially at the vertical axis about which the front carrying wheels of 30 the truck are adapted to be moved for guiding the truck regardless of the angular position of such carrying wheels. It is another object of my invention to provide a construction of this type comprising pawl and 35 ratchet mechanism by which power is transmitted from the operating lever to the arms or levers by which the elevating frame is raised. It is another object of my invention to 40 provide a construction of this type comprising a lifting pawl and a holding pawl, together with means for lifting said pawls out of operative position, such means being arranged so as to insure the lifting pawl being thrown out of operation before the holding pawl is moved out of operative position. 45 It is another object of my invention to improve trucks in sundry details hereinafter pointed out. The preferred means by which I have accomplished my several objects are

illustrated in the drawings and are hereinafter specifically described. That which I believe to be new and desire to cover by this application is set forth in the claims.

In the drawings:

Fig. 1 is a side view of my improved truck 60 with the elevating frame in lowered position, the upper end of the handle or tongue being broken away;

Fig. 2 is a view similar to Fig. 1, but showing the elevating frame in raised position;

Fig. 3 is a top or plan view of my improved truck, the handle or tongue being shown in section;

Fig. 4 is a vertical cross-section taken substantially on line 4—4 of Fig. 3;

Fig. 5 is a perspective view of the yoke constituting the connecting means between the elevating frame and the fixed frame at the rear end of the truck;

Fig. 6 is an enlarged detail, being a side view of the operating parts at the front end of the truck;

Fig. 7 is an enlarged detail, being substantially a cross-section taken on line 7—7 of Fig. 3; and

Fig. 8 is a vertical transverse section taken substantially on line 8—8 of Fig. 6.

Referring to the several figures of the drawings in which corresponding parts are indicated by the same reference characters,—

15—16 indicate the side bars of the fixed frame of the truck being held together at their forward ends by means of a heavy channel iron 17 (see Fig. 6). A transversely 90 extending axle 18 supports carrying wheels 19—20 in position at the rear end of the fixed frame. A yoke 21 is revolubly mounted by means of arms 22—23 about the axle 18, the yoke 21 being connected by means of a 95 pin or bolt 24 with the rear ends of the longitudinally-extending bars of the elevating frame 25. A heavy bar or shaft 26 is revolubly mounted upon the plate 17 at the forward end of the truck, being supported by 100 bearings 27 on said plate. Arms 28 are flexibly mounted upon the shaft 26, the upper ends of said arms 28 being pivotally connected with the side bars of the elevating frame 25 by means of pins or bolts 29 of any 105 suitable type. As will be readily understood from an inspection of the drawings, when the shaft 26 is moved in Fig. 1 so as to carry

the arms 28 into the position shown in Fig. 2, the arms 22-23 of the yoke 21 are likewise moved in counterclockwise direction in said Fig. 1 about the axle 18, the elevating frame 25 being raised relative to the fixed frame comprising the side bars 15-16.

As is best shown in Fig. 3, the elevating frame 25 comprises a transversely-extending angle iron 30 near its forward end, and the fixed frame comprises a transversely-extending bar 31 near its rear end. The bars 30-31 are connected by the members 32-33 of a dash-pot or check-valve of any suitable type, the members being pivotally connected with the bars 30-31 so as to permit the desired freedom of movement of the elevating frame relative to the fixed frame. As is shown in dotted lines in Fig. 3, the bars 30-31 are also connected by a coiled spring 34 in connection with the check-valve, the spring being adapted to move the elevating frame downward against the action of the check-valve when the elevating frame is released from its elevated position with no load thereon.

As is best shown in Fig. 4, the channel iron 17 at the front end of the truck is provided with a sleeve member 35 rigidly connected in position thereon for the connection 30 of the front axle member of the truck with the fixed frame so as to be revoluble about a vertical axis thereon. The axle member in the construction shown is indicated by the numeral 36, being in the form 35 of a casting with axles 37-38 secured therein for the reception of carrying wheels 39-40, respectively. The axle member is revolubly mounted in the sleeve 35 by means of a two-part neck comprising a lug 41 40 formed integrally with the casting 36 and a neck portion 42 having toothed engagement with the lug 41 and held in position within the sleeve 35 by means of a pin or bolt 43, the upper end of the neck portion 42 being 45 provided with a retaining flange or plate 44. At its forward edge portion, the plate 44 is provided with standards 45 between which a steering lever or handle 46 is pivotally mounted by means of a pin or bolt 47. As 50 is best shown in Fig. 6, the portion of the steering lever or handle 46 adjacent to the pivot pin 47 is offset so as to permit the handle to be lowered without coming in contact with the forward flange of the channel iron 17. As will be readily understood, the steering lever or handle 46 can be raised and lowered about the pivot pin 47 for manipulating the truck as desired, and the front axle member 36 can be shifted angularly relative to the truck through the medium of the steering lever for guiding the truck, the arrangement being such that the steering lever can be swung laterally through an angle of 180° or more without bringing the 55 standards 45 into contact with the remaining

operating parts mounted upon the heavy plate 17.

The operating means by which power is applied from the handle or lever 46 for turning the shaft 26 for raising the elevating frame 25 relative to the fixed frame, comprises a gear 48 fixedly mounted upon the shaft 26, such gear being in engagement with a pinion 49 fixedly mounted upon a short shaft 50 which is revolvably mounted in standards 51 rising from the plate 17. The shaft 50 has fixedly mounted thereon between the standards 51 a ratchet wheel 52, the arrangement being such that when the ratchet wheel 52 is rotated in clockwise direction in Fig. 6 the shaft 26 is turned in counterclockwise direction in said figure for raising the elevating frame 25.

Means is provided for rotating the ratchet wheel 52 in clockwise direction in Fig. 7, comprising a rocking lever 53 which is loosely mounted upon the shaft 50. In the construction shown, the lever 53 is in the form of a yoke with its arms on opposite sides of the ratchet wheel 52, as is best shown in Fig. 3, such lever 53 having a pawl 54 pivotally mounted thereon by means of a pin 55, the pawl 54 being adapted to engage the ratchet wheel 52. The forward end of the rocking-lever 53 is rounded, as is best shown in Figs. 6 and 7, being located substantially at or in line with the vertical axis about which the front axle member 36 is adapted to turn relative to the plate 17. The forward end of the lever 53 in this position is adapted to be engaged by a roller 56 revolvably mounted in the lower end of the handle or lever 46, such roller being revolvably mounted in position by means of a pin 57. As will be readily understood, when the handle or lever 46 is given a downward stroke, the roller 56 by its engagement with the lever 53 gives the lever a clockwise movement in Fig. 7 for causing a slight counterclockwise rotation of the shaft 26 in said figure for causing a partial raising movement of the frame 25. Means is provided as hereinafter described for holding the ratchet wheel 52 against reverse rotation when the pressure is withdrawn from the pawl 54 for another operative stroke of the lever 46. The roller 56 when in its lowermost position is located substantially at the vertical axis of the axle member 36, whereby such roller is adapted to operatively engage the lever 53 in whatever angular position the lever 46 may stand relative to the fixed frame of the truck. At the end of a full operative stroke of the lever 46, the rear end of the lever 53 is brought into contact with the shaft 26, serving to limit the stroke of the parts so as to prevent the roller 56 passing out of operative position below the lever 53. The means for holding the ratchet wheel 52 and the shaft 50 against rotation in 130

- counterclockwise direction in Fig. 7, either for holding the elevating frame in raised position for transportation or for holding such frame in partially raised position for the next succeeding operative stroke of the lever 46, comprises a shaft 58 which is revolubly mounted within a sleeve 59 which in turn is revolubly mounted in one of the standards 27 and one of the standards 51, as is best shown in Fig. 8. As is best shown in this figure, the shaft 58 extends beyond the ends of the sleeve 59, one end portion of the shaft 58 having a bearing in the standard 51 adjacent to the pinion 49. The outer end of the shaft 58 has fixedly mounted thereon a lever 60, the rear end of which is connected by means of a coiled spring 61 with the plate 17, the spring 61 being adapted to hold the lever 60 and the shaft 58 yieldingly turned to the limit of their motion in clockwise direction in Fig. 6. The shaft 58 has fixedly mounted thereon a dog or pawl 62 in position to engage the ratchet wheel 52, the spring 61 serving to hold the pawl 62 yieldingly in engagement with the ratchet wheel 52. Inasmuch as the pawl 62 supports the entire weight of the elevating frame and its load, I have reinforced the construction by providing lugs 63 extending from the inner faces of the standards 51 for supporting the shaft 58 immediately adjacent to the pawl 62. Means is provided for throwing the pawls 54 and 62 out of operative position relative to the ratchet wheel 52 whenever it is desired to lower the elevating frame 25. This means comprises the sleeve 59 above referred to having fixedly mounted thereon an arm 64 adjacent to the outer face of one of the standards 51. The arm 64 is adapted, upon the rotation of the sleeve 59 in counterclockwise direction in Fig. 7, to engage the lower end of an arm 65 connected with the pawl 54 for raising the pawl out of the position shown in Fig. 6 into the position shown in Fig. 7 out of contact with the ratchet wheel 52. The sleeve 59 and the arm 64 are normally held turned to the limit of their movement in clockwise direction in Fig. 7 by means of a spring 66 connected with a rearwardly-extending arm 67 mounted on said sleeve (see Figs. 3 and 6). Means is provided for turning the sleeve 59 in counterclockwise direction in Figs. 6 and 7 against the action of the spring 66, comprising a foot lever 68 fixedly mounted on said sleeve and extending forward therefrom adjacent to the lever 60. As is best shown in Fig. 3, the foot plate 69 of the lever 68 extends laterally into position over the lever 60, whereby upon an extended downward stroke of the lever 68 the lever 60 is also moved downward against the action of the spring 61. By this arrangement and construction, upon the initial downward movement of the lever 68 against the action of the spring 66, the pawl 54 is moved out of engagement with the ratchet wheel 52; thereafter, in the continued downward movement of the lever 68, the lever 60 is moved downward with the lever 68 serving to throw the pawl 62 also out of engagement with the ratchet wheel 52. As will be readily understood, when both of the pawls 54 and 62 are held out of engagement with the ratchet wheel 52, the elevating frame 25 is free to move downward against the action of the check valve 32—33, either under the impetus of the load upon the elevating frame or of the spring 34 positioned underneath the check-valve. What I claim as my invention and desire to secure by Letters Patent, is—
1. A lifting truck comprising a wheeled frame, an elevating frame mounted thereon to move longitudinally and vertically, a vertically swinging steering lever, a rocking member mounted on said wheeled frame and adapted to be directly engaged and actuated by said steering lever, and means actuated by said rocking member for raising said elevating frame, said steering lever being arranged to swing laterally independently of said rocking member meanwhile maintaining its operative relation thereto. 80
  2. A lifting truck comprising a wheeled frame, an elevating frame carried thereby, a vertically swinging steering lever, a rocking member mounted on said wheeled frame and adapted to be directly engaged and actuated by said steering lever, and pawl and ratchet mechanism actuated by said rocking member for raising said elevating frame, said steering lever being arranged to swing laterally independently of said rocking member. 85
  3. A lifting truck comprising a wheeled frame, an elevating frame carried thereby, a rocking lever mounted on said wheeled frame, a steering lever adapted to engage and operate said rocking lever and arranged to swing laterally independently thereof meanwhile maintaining its operative relation thereto, and gearing operated by said rocking lever for raising said elevating frame. 90
  4. A lifting truck comprising a wheeled frame, an elevating frame carried thereby, a rocking lever mounted on said wheeled frame, a steering lever adapted to directly engage and operate said rocking lever and arranged to swing laterally independently thereof meanwhile maintaining its operative relation thereto, and rotating means mounted on said wheeled frame and operated by said rocking lever for raising said elevating frame. 105
  5. A lifting truck comprising a wheeled frame, an elevating frame mounted thereon and movable longitudinally and vertically, a vertically swinging steering lever, gearing mounted on said wheeled frame and connect- 110

ed with said elevating frame for moving the same longitudinally and vertically, and pawl and ratchet mechanism adapted to be actuated by said steering lever in any steering position thereof for rotating said gearing.

6. In a truck, the combination of a frame, an elevating frame movable up and down relative thereto, means comprising a rotary member for moving said elevating frame upward relative to said first-named frame, means comprising pawl and ratchet mechanism for operating said rotary member, a lever movably mounted relative to said operating means adapted to be swung laterally relative to said frames and adapted to have operative engagement with said operating means in whatever angular position the lever may stand relative to the frames, a holding pawl adapted to cooperate with said ratchet for permitting successive operative strokes of said lever, a second lever adapted by a downward stroke to throw said holding pawl out of operative position, and a third lever adapted by a partial downward stroke to throw said operating pawl out of operative position and adapted thereafter by a continued downward stroke to cause a downward stroke of said second lever for throwing said holding pawl out of operative position.

7. In a truck, the combination of a frame, an elevating frame movable up and down relative thereto, means comprising a rotary member for moving said elevating frame upward relative to said first-named frame, means comprising pawl and ratchet mechanism for operating said rotary member, a lever movably mounted relative to said operating means adapted to be swung laterally relative to said frames and adapted to have operative engagement with said operating means in whatever angular position the lever may stand relative to the frames, a holding pawl adapted to cooperate with said ratchet for permitting successive operative strokes of said lever, a transversely-extending sleeve revolvably mounted on said first-named frame, a second lever for rotating said sleeve, an arm projecting from said sleeve adapted upon a downward stroke of said second lever to throw said operating pawl out of operative position, and other means actuated thereafter by a continued downward stroke of said second lever for throwing said holding pawl out of operative position.

8. In a truck, the combination of a frame, an elevating frame movable up and down relative thereto, means comprising a rotary member for moving said elevating frame upward relative to said first-named frame, means comprising pawl and ratchet mechanism for operating said rotary member, a lever movably mounted relative to said operating means adapted to be swung laterally

relative to said frames and adapted to have operative engagement with said operating means in whatever angular position the lever may stand relative to the frames, a transversely-extending sleeve revolvably mounted 70 on said first-named frame, a second lever for rotating said sleeve, an arm projecting from said sleeve adapted upon a downward stroke of said second lever to throw said operating pawl out of operative position, a 75 shaft extending through said sleeve, a pawl fixedly mounted on said shaft adapted to engage said ratchet for holding it against reverse rotation for permitting successive operative strokes of said first-named lever, 80 and a third lever fixedly mounted on said shaft and adapted to be engaged by said second lever for throwing said holding pawl out of operative position upon a continued downward stroke of said second lever after 85 said operating pawl has been thrown out of operative position.

9. In a truck, the combination of a main frame, an elevating frame movable up and down relative thereto, means comprising a 90 rotary member mounted on said main frame for moving said elevating frame upward relative to said first-named frame, a ratchet adapted to revolve with said rotary member, a lever pivotally mounted on the axis about 95 which said ratchet rotates, a pawl movably mounted on said lever in position for operatively engaging said ratchet, and a second lever movably mounted relative to said operating means adapted to be swung laterally relative to said frames and adapted to have operative engagement with said first-named lever for raising said elevating frame in whatever angular position said second lever may stand relative to said frames.

10. In a truck, the combination of a frame, an elevating frame movable up and down relative thereto, a shaft, means actuated by the rotation of said shaft in one direction for raising said elevating frame, a ratchet 110 fixedly mounted on said shaft, a yoke lever having its arms mounted on said shaft on opposite sides of said ratchet, a pawl movably mounted on said yoke lever in position to engage said ratchet, and a second 115 lever movably mounted relative to said yoke lever adapted to be swung laterally relative to said frames and adapted to have operative engagement with said yoke lever for raising said elevating frame in whatever 120 angular position said second lever may stand relative to said frames.

11. In a truck, the combination of a frame, an elevating frame movable up and down relative thereto, a shaft, means actuated by the rotation of said shaft in one direction for raising said elevating frame, a ratchet fixedly mounted on said shaft, a yoke lever having its arms mounted on said shaft on opposite sides of said ratchet, a 130

pawl movably mounted on said yoke lever in position to engage said ratchet, a second lever movably mounted relative to said yoke lever adapted to be swung laterally 5 relative to said frames and adapted to have operative engagement with said yoke lever for raising said elevating frame in what-

ever angular position said second lever may stand relative to said frames, and means for limiting the stroke of said yoke lever where- 10 by said two levers are prevented from moving out of operative position relative to each other.

ARTHUR M. BARRETT.
